UNITED STATES PATENT OFFICE.

ROBERT C. HOPKINS, OF ALLIANCE, OHIO.

OIL MILL.

Application filed April 3, 1926. Serial No. 99,586.

The invention relates to mills for grinding or breaking up the sludge and heavy particles of oil used for fuel in oil fired furnaces and the like.

5 In using fuel oil, for firing furnaces, considerable trouble has been experienced by heavy particles of oil and sludge stopping up valves and burners and interfering generally with the circulating lines. In the past it has 10 been customary to remove these heavy particles and sludge by providing screens in the circulating lines but these screens must be frequently removed and the heavy particles and sludge cleaned therefrom or in a short 15 time the line will become stopped.

In carrying out the present invention all of the heavy particles of oil and sludge are ground in the improved oil mill not only preventing the waste of these heavier portions of 20 the oil but also preventing stopping up of the lines and the loss of time attendant upon such trouble.

The object of the invention is to provide an oil mill comprising a vertical chamber into 25 which the oil to be treated is admitted at a point spaced from the top of the chamber and substantially tangential thereto, the grinding mechanism comprising a plurality of rolling elements located in the bottom of 30 the chamber and arranged to be continuously driven to grind any sludge or heavy particles of oil which will naturally descend by gravity to the bottom of the chamber, an outlet being provided in the top of the chamber and 35 preferably at the center thereof, to carry off the light oil to the line or to any suitable container which may be provided for the purpose.

The above and ancillary objects may be attained by providing a vertical cylindrical chamber, the oil inlet being provided at one side thereof and spaced from the top of the chamber in order to give the incoming oil a whirling motion inside of the chamber. The 45 outlet being at the center of the top of the chamber, which is the area of the light oil and of substantially no motion, only the lighter portions of the oil in the chamber will pass through the outlet.

50 The heavier portions of sludge will by centrifugal force gradually flow to the outer portion of the chamber and contact with the side walls thereof, and then by a difference in specific gravity these heavier portions will

settle down to the lower end of the tank and by 55 centrifugal force will be carried to the outside and into the ball or roller race where the action of the balls or rolls grinds these heavier portions and sludge, and as the grinding process continues the lighter portions of oil will 60 separate, dissolve and rise to the top flowing out with the oil stream through the outlet pipe.

An embodiment of the invention is illustrated in the accompanying drawings, in 65 which—

Figure 1 is a side elevation, partly in section, of the improved oil mill showing a single race of grinding balls for grinding the sludge and heavy particles of oil; 70

Fig. 2, a vertical sectional view of the lower portion of a slightly modified form of the mill showing a plurality of races of grinding balls decreasing in diameter from the outside toward the center of the mill; 75

Fig. 3, a similar view of a still further modification showing tapered grinding rollers, and

Fig. 4, a variation of the form shown in Fig. 3, showing the tapered rollers provided with teeth arranged to mesh with teeth 80 upon the bottom race member of the mill.

Similar numerals of reference indicate corresponding parts throughout the drawings.

The mill comprises a vertical tank 1, preferably cylindrical and provided with an oil-inlet pipe 2 at a point intermediate the top and bottom of the tank and preferably extending tangentially into the peripheral portion of the tank to cause a whirling motion of the oil within the tank. 85

The oil outlet pipe 3 is located at the central portions of the top of the tank which is the area of the lightest oil and of substantially no motion of the oil. 90

The mill may be arranged to be driven by 95 means of an electric motor 4, mounted upon a bracket 5, at one side of the tank, the motor pulley 6 being connected, as by the belt 7, with the drive pulley 8, upon the worm shaft 9, journaled in suitable bearings 10 and 11, 100 mounted upon the tank in any suitable manner.

This worm shaft extends into the tank and is provided with the worm 12, arranged to mesh with a worm wheel 13, upon the vertical shaft 14, axially located within the tank and journaled in bearings 15 and 16. 105

An annular raceway 17 is formed at the

lower end of the tank being located at the peripheral portion thereof, to receive the grinding balls 18 which may substantially fill the raceway.

5 In order to drive the grinding balls, an inclined radial arm 19 is fixed upon the shaft 14, and extended down between two of the balls, so that the grinding balls are continuously driven around the raceway by the rotation of 10 the shaft 14, grinding the sludge and heavy particles of oil which descend by specific gravity and are continuously thrown outward to the raceway by centrifugal action of the oil, the light oil continuously ascending through 15 the axial center of the tank to the outlet pipe 3.

In the form of the invention shown in Fig. 2, a plurality of raceways 17^a may be provided at the lower end of the tank, a series of 20 courses of grinding balls 18^a, preferably diminishing in size toward the center of the tank, being located in the raceways and arranged to be all driven by one or more arms 19^a carried upon the shaft 14.

25 In Fig. 3, the bottom of the tank may be provided with a single outwardly inclined raceway 17^b, in which are located a series of conical rollers 18^b arranged to be driven by one or more arms 19^b carried by the shaft 14.

30 A modification of the form shown in Fig. 3 is illustrated in Fig. 4, in which the inclined raceway 17^c may be provided with teeth 17^c forming substantially a fixed bevel gear upon which the rollers 18^c are mounted.

35 These rollers are tapered and provided with teeth 18^c, being in the form of a plurality of bevel pinions journaled at their outer ends in the arms 19^c carried by the shaft 14.

In each of the forms of the invention the 40 action is substantially the same, the heavier particles of oil and the sludge being thrown by centrifugal force to the peripheral portion of the tank and descending into the raceways to be ground by the rolling elements, the 45 lighter portions of the oil continuously ascending through the axial center of the tank to the outlet pipe.

In each case a drain pipe 21 may be provided in the bottom of the tank to remove any 50 unground sediment which may collect therein, as well as to drain off water which will separate from the oil and settle to the bottom.

I claim:

55 1. An oil mill including an upright chamber, means for admitting oil tangentially to the chamber and for producing centrifugal action of the oil to separate the oil into light and heavy portions and to allow the heavy 60 portions of the oil to settle downward to the bottom of the chamber, grinding means in the peripheral portion of the bottom of the chamber for grinding heavy portions of the oil, and an oil outlet at the axial center of the 65 top of the chamber.

2. An oil mill including an upright chamber, means for admitting oil tangentially into the chamber at a point intermediate the top and bottom of the chamber, means for separating the oil into light and heavy portions to allow the heavy portions of the oil to settle downward to the bottom of the chamber, grinding means in the peripheral portion of the bottom of the chamber for grinding heavy portions of the oil, and an oil outlet 70 at the axial center of the top of the chamber. 75

3. An oil mill including an upright chamber, means for admitting oil at a point intermediate the top and bottom of the chamber, means for separating the oil into light and 80 heavy portions, grinding means at the bottom of the chamber for grinding heavy portions of the oil and an oil outlet at the axial center of the top of the chamber.

4. An oil mill including an upright chamber, means for admitting oil to the chamber, means for separating the oil into light and heavy portions, a raceway at the bottom of the chamber, rolling elements in the raceway, means for driving said rolling elements 85 around the raceway to grind heavy portions of the oil, and an oil outlet at the axial center 90 of the top of the chamber.

5. An oil mill including an upright chamber, means for admitting oil to the chamber, 95 means for separating the oil into light and heavy portions, a raceway at the bottom of the chamber, rolling elements decreasing in diameter from the periphery toward the center of the chamber, located in said raceway, 100 means for driving said rolling elements around the raceway to grind heavy portions of the oil and an oil outlet at the axial center of the top of the chamber.

6. An oil mill including an upright chamber, means for admitting oil to the chamber, means for separating the oil into light and heavy portions, a raceway at the bottom of the chamber, rolling elements in the raceway, a driven shaft in the chamber, an arm 110 carried by the shaft and associated with the rolling elements for driving them around the raceway to grind heavy portions of the oil, and an oil outlet at the axial center of the top of the chamber. 115

7. An oil mill including an upright chamber, means for admitting oil to the chamber, means for separating the oil into light and heavy portions, a raceway at the bottom of the chamber, tapered rolling elements in the raceway, means for driving said rolling elements around the raceway to grind heavy portions of the oil, and an oil outlet at the axial center of the top of the chamber. 120

8. An oil mill including a chamber, means for admitting oil to the chamber, means for separating the oil into light and heavy portions, a toothed raceway at the bottom of the chamber, toothed tapered rolling elements in the raceway, means for driving the rolling 125 130

elements around the raceway to grind heavy portions of the oil, and an oil outlet at the top of the chamber.

9. An oil mill including an upright chamber, means for admitting oil to the chamber, grinding means at the bottom of the chamber, a worm wheel within the chamber for driving said grinding means, a worm within

the chamber for driving the worm wheel, means for driving the worm, and an oil outlet at the axial center of the top of the chamber. 10

In testimony that I claim the above, I have hereunto subscribed my name.

ROBT. C. HOPKINS.
